(57) CLAIM

The ornamental design for a transmitting temperature sensor for bath tub, as shown and described.

DESCRIPTION

FIG. 1 is a perspective view of a transmitting temperature sensor for bath tub showing my new design;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a bottom plan view thereof; and,

FIG. 7 is a reduced perspective view showing the transmitting temperature sensor for bath tub in use; the broken lines depict environmental structure for illustrative purposes only and form no part of the claimed design.
